STEAM WASHER

Filed July 11, 1924

Inventor:
Charles E. Bean,
by Robert Burns,
Atty.

UNITED STATES PATENT OFFICE.

CHARLES EVANS BEAN, OF KANSAS CITY, KANSAS.

STEAM WASHER.

Application filed July 11, 1924. Serial No. 725,273.

To all whom it may concern:

Be it known that I, CHARLES EVANS BEAN, a citizen of the United States, residing at Kansas City, in the county of Wyandotte 5 and State of Kansas, have invented a certain new and useful Improvement in Steam Washers, of which the following is a specification.

This invention relates to that class of 10 household washing apparatus in which a flow of hot water and steam from the lower part of the containing vessel is discharged in a continuous manner upon the clothes in the upper portion of the vessel, the clothes 15 being stirred or turned by the usual hand operated dolly mechanism as required, and more especially to the type of such washers which forms the subject matter of my prior Patent No. 1,202,150, dated October 24, 20 1916.

The object of the present improvement is to provide a structural formation and combination of parts by means of which an opposed retarding action is set up in opposition 25 to the normal turning movement of the stirrer or dolly of the apparatus, to attain an effective change or turning of the clothes being washed, and in connection with such changing or turning action provide means 30 whereby the hot water and steam are discharged into the clothes in a thorough and effective manner, all as will hereinafter more fully appear.

In the accompanying drawings:—

Fig. 1 is a central vertical sectional elevation of a steam washer having the present improvement applied.

Fig. 2, is a horizontal section on line 2—2, Fig. 1.

Like reference numerals indicate like parts in both views.

As shown in the drawing, the casing or container 1 of the present washer is of the usual cylindrical form, closed at its lower 45 end by a fixed bottom 2, and at top by a removable cover 3, in which the usual or conventional vertically arranged stirrer of dolly 4 is revolvably mounted, as well as the operating gear wheel 5, gear sector 6 and operating handle 7, substantially the same as in my 50 aforesaid Patent No. 1,202,150.

A horizontal partition 8, by which circula-

tion of hot water and steam within the casing 1 is directed and controlled, has the usual position within the casing 1 a short 55 distance above the bottom 2 of the same, and is removably supported in such position by legs 9 as shown. In the present improvement said partition is of a saucer shape with its upwardly flaring marginal portion 10 60 formed with a plurality of raised nodes or protuberances 11 of a rounded form and elliptical outline and disposed circularly around the mid-width of said marginal portion 10 as shown. 65

Such special formation and arrangement of the nodes or protuberances 11, is a material part of the invention, in that the same has been found after extended practical tests and changes with and in the older patented 70 constructions of applicant, to attain a much more effective turning, rubbing and washing action on the lower part of the mass of clothes, operated on.

The partition 8 has approximately the 75 same diameter as the internal diameter of the container 1 and its periphery is formed with notches 12 adapting the partition to engage and fit the plurality of vertical conduits now to be described.

The vertical conduits 13 above referred to are of a semi-circular form in horizontal section and of a tapering form from bottom to top, and are fixedly secured in circular spaced relation on the inner face of the container 1, as shown. Each conduit 13 is open 80 at bottom to the chamber beneath the partition 8 aforesaid, and is also open at its upper end into the upper portion of the clothes holding chamber of the container 1, and in addition a vertical series of orifices 14 are 85 formed in the inwardly facing portion of the wall of a conduit 13, the construction being adapted to attain an effective and thorough discharge of the flow of hot water 90 and steam, as the same passes up the conduits 13, into the mass of clothes as the same is changed and turned in manner above set forth.

Having thus fully described my invention 100 what I claim as new and desire to secure by Letters Patent, is:

In a steam washer, the combination of a casing provided with vertical conduits at its

sides, a removable cover for the casing carrying a dolly, a removable horizontal partition supported in the casing a distance above the bottom of the said casing and formed

5 with a central plane portion and an upwardly flared marginal portion formed in turn with a circular series of nodes of an

elliptical shape and arranged in separated relation at the mid-width of said marginal portion of the partition.

10

Signed at Kansas City, Kansas, this 5th day of July 1924.

CHARLES EVANS BEAN.
